UNITED STATES PATENT OFFICE.

WILLIAM F. CROCKETT, OF BARNETT, MISSOURI.

RAILROAD TIE.

Application filed June 11, 1927. Serial No. 198,169.

My present invention has reference to a metal tie and means for effectively securing rails thereon.

An object is the provision of means, in a construction of this character for securely locking various sizes and types of railway rails on a metal tie, and further wherein, either a narrow or a wide gage track may be produced.

10 A still further object is to provide a hollow substantially rectangular metal tie with combined gage and rail plates that have a toothed engagement with the tie and are, therefore, laterally adjustable thereon, and
 15 further wherein the base flanges of the rails are engaged by rail clamps of a particular and peculiar construction and which clamps in turn are engaged by adjustable wedge means which sustain the clamps in locking engagement with the rails and likewise sustain the said clamps firmly locked on the tie.

20 To the attainment of the above broadly stated objects and others which will present themselves as the nature of the invention is better understood, the improvement also resides in certain other novel features of construction, combination and operative association of parts, one satisfactory embodiment of which is disclosed by the accompanying drawings.

25 In the drawings:

Figure 1 is a top plan view of the improvement, showing rails locked on the tie. Figure 2 is a substantially central longitudinal sectional view through the construction illustrated in Figure 1.

30 Figure 3 is an end view thereof.

Figure 4 is a sectional view approximately on the line 4—4 of Figure 2.

40 Figure 5 is a perspective view of one of the rail clamps.

Figure 6 is a similar view of one of the combined rail and gage plates.

45 As disclosed by the drawings, a tie in accordance with this invention, is hollow and is of a substantially rectangular formation. However, the sides of the hollow tie 1 are arranged at an outward angle with respect to the flat top and base of the tie. These outwardly inclined sides 2, when contacted by the road bed effectively retain the tie embedded therein.

50 The flat top of the tie 1, at points adjacent to the ends thereof, is recessed both longitudinally and transversely to provide channel portions that afford rail seats. The

bottoms of these channels are formed with saw teeth 3, and are each provided with a pair of spaced openings, one of which being disposed in a line with the inner wall provided by the channel and is indicated by the numeral 4, and the other indicated by the numeral 5, is disposed a suitable distance from the opposite side wall provided by the channel.

55 The combined rail and gage plates are of similar construction and are indicated in the drawings by the numeral 6. Each of these plates has its under face formed with saw teeth 7 to coengage with the teeth in the channel portions of the tie. Each of the plates 6 has its edges centrally notched, as at 8 and 9, respectively. The notches 8 and 9 are designed to register with the openings 4 and 5 in the tie. The plate 6, adjacent to its outer edge, is formed with an upstanding enlargement, providing the same with an inner shoulder 10, and the opening 9 passes through this enlarged portion of the plate. The shoulders 10 are designed for 60 contacting engagement with the outer base flanges of the rails 11 which rest on the plates 6. As the plates are designed for adjustment on the depressed portions providing the channeled rail seats 3 it will be apparent that the rails 11 may be properly gaged so that either narrow or wide gaged tracks can be thus produced. It will be further apparent as the description progresses that rails of different sizes may be arranged 65 upon the tie and effectively locked thereto.

The rail clamps 12 are each in the nature of a substantially rectangular block. The blocks 12 have their inner edges notched, as at 13, and these notches coincide with the cross sectional shape of the outer portions of the base flanges of the rails 11, the said portions of the rails being received in the said notches. Each rail clamp from its outer end is centrally slotted, as at 14. The lower walls provided by the slots 14 are rounded. The inner walls provided by the slots in the inner rail clamps are straight, that is, the same are arranged at a right angle with respect to the longitudinal plane 70 of these clamps but the inner walls provided by the slots in the outer clamps 12 are arranged at an angle, as indicated by the numeral 15.

75 Passing through the bifurcated portion of the rail clamps and, of course, disposed in the hollow body of the tie 1, there are wedge

members 16. Each of the wedges has its inner and reduced end formed with an angular extension 16 which is round in cross section and which is threaded and these threaded portions or shanks 16 pass freely through angle openings 17 in the top of the tie 1. The openings 17 are surrounded by upwardly directed bosses 18 and the outer faces of the bosses are arranged at angles. The threaded shanks 16 are engaged by nuts 19 which, of course, contact with the outer faces of the bosses. By adjusting the nuts a longitudinal as well as a downward swinging movement will be imparted to the wedge members 16. This movement of the wedge members will cause the outer rail clamps 12 to assume an angular or canting position as disclosed by Figure 2 of the drawings, forcing these clamps, both downwardly and inwardly with respect to the rails 11, and consequently effectively lock the rails 11 on the tie against vertical or canting movement, the binding action, however, not being sufficient to impair the longitudinal movement 25 of the rails incident to expansion and contraction.

The improvement provides for the effective locking of rails of different sizes on the tie, for gaging the said rails and thereby producing a track of either a wide or narrow gage.

Having described the invention, I claim:—

1. The combination, a hollow tie, combined gage and rail plates on the tie, inter-engaging means between the plates and the tie, rail engaging clamps passing through the ends of the gage plate and entering the tie, wedges in the hollow tie passing through the clamps, and means for adjustably locking the wedges to the tie.

2. The combination, a hollow tie, combined gage and rail plates on the tie, inter-engaging means between the plates and the tie, rail engaging clamps passing through the ends of the gage plate and entering the

tie, said clamps comprising bifurcated blocks, a wedge passing through each clamp for frictionally engaging with the inner walls thereof, means for longitudinally adjusting the wedges and for locking the same to the tie, whereby to cause the canting of the outer rail clamps and the binding engagement of the inner rail clamps against the tie.

3. The combination with a hollow metal tie having recessed portions affording rail seats adjacent to the ends thereof, and the bottom walls of the seats having transverse saw teeth, and provided with openings, one of which being disposed in a line with the inner shoulder provided by the said combined gage and rail plate in each of the seats and each of the said plates having its under face formed with saw teeth to engage with the teeth in the seats, each of said plates being notched to align with the openings in the seats, said plates having outer upstanding shoulders for contact with the outer edges of the bases of the rails when arranged on the plates, rail clamps each including a bifurcated block having notches to engage said edges of the base flanges of the rails, said clamps passing through the openings in the seats and through the notches in the plates, the inner wall provided in the bifurcated portions of the outer clamps being disposed at an angle with respect to the longitudinal plane of said clamps, wedge members arranged in the hollow tie and received through the bifurcated rail clamps, each of said wedge members having an inner angle shank which is round and which is threaded and which passes freely through an angle opening in the top of the tie, bosses surrounding the openings in the ties and having outer angle faces and nuts screwed on the stems and contacting with the said faces of the bosses.

In testimony whereof I affix my signature.

WILLIAM F. CROCKETT.
